UNITED STATES PATENT OFFICE.

IRA W. FOLTZ, OF CHICAGO, ILLINOIS.

FURNACE.

1,274,155.

Specification of Letters Patent. Patented July 30, 1918.

Application filed March 6, 1916. Serial No. 82,414.

To all whom it may concern:

Be it known that I, IRA W. FOLTZ, a citizen of the United States of America, and a resident of Chicago, county of Cook, and 5 State of Illinois, have invented certain new and useful Improvements in Furnaces, of which the following is a specification.

This invention relates to furnace constructions and its object is mainly to provide 10 proved means for mixing heated air in required proportions with the gases distilled from the burning fuel.

An illustrative embodiment of this invention is shown in the accompanying drawings, 15 in which—

Figure 1 is a longitudinal vertical section on the line 1—1 of Fig. 2, of a furnace constructed according to this invention.

Fig. 2 is a sectional plan view taken on 20 the line 2—2 of Fig. 1.

Fig. 3 is a transverse vertical section taken on the line 3—3 of Fig. 1.

Fig. 4 is a detail in plan of part of the 25 grate.

It is well known that the gases generated by burning coal and other fuels, and particularly the carbon contained in said gases, may be completely burned if mixed with a sufficient quantity of hot air, and ignited 30 before said gases are permitted to cool to any appreciable extent.

The present invention provides an improved means for heating, mixing and delivering air and gases in a region of comparatively high heat in the furnace. The invention also provides an air and gas mixing device which in no way interferes with the stoking and operation of the furnace, and may be easily applied to many standard 40 makes of furnaces which ordinarily have little, if any, provision for completely consuming the gases distilled in such furnaces.

The drawings show a standard type of furnace and boiler without alteration of the 45 form of the fire-box and combustion chamber, or the grate and the supporting brick work. The boiler 1 surrounds the flues 2 and the fire-box lining 3. The fire-box is provided with a grate 4 in the usual location 50 supported by the grate rests 5. The perforated conduit 6 is preferably located at each side of the grate and is open at its lower end to provide a passage for air from the ash-pit 7 into the sides of the fuel body 55 on the grate.

Conduits 6 are preferably provided with perforated extensions 8 at the front of the furnace, as shown in Fig. 2. Communicating with said conduits at each forward corner of the furnace is an upstanding pipe 60 or conduit 9, which extends upwardly close to the roof 10 of the fire-box and then to the rear end of the fire-box or into the combustion chamber, and returns to the forward end of the fire-box where it is provided with an outlet 11. The object of so arranging these conduits is to provide for highly heating the air passing through the same before said air is delivered to the compartment or division 12 of the furnace where 65 it is mixed with gases rising from the fuel.

At approximately one-fourth the distance from the rear end of the fire-box is a transversely extending dividing wall 14 suitably designed to provide space between the lower 70 edge of the same and the grate 4, this space being more or less closed up by the fuel during ordinary operation of the furnace.

The wall 14 is made hollow, providing a vertical passage 15 having a plurality of inlets 16 communicating with the division or compartment 12 of the furnace, and an outlet 17 at its lower edge. The air heating conduits 9 are preferably provided, in addition to the outlets 11, with an outlet 18 75

communicating with the passage in the partition wall 14 and are also preferably provided with small perforated pipes 19 communicating with the compartment or division 20. The outlet into the partition wall 14 may be provided for by a pipe 21 connecting the conduits 9 at the rear of partition 14 and having an extension 22 entering the partition wall 14. The passage of air 80 upwardly through the grate into division 20 may be more or less restricted by closing some of the apertures in the rear grate bars, as indicated in Fig. 4 by numeral 23. Accordingly, in the operation of the furnace 85

the lighter gases rising from the fuel will be mainly collected in the compartment 12 where they are mixed with heated air delivered into said compartment through the outlets 11 in conduits 9. The mixture then passes under the arch or through inlets 16 90 into the hollow wall 14 where additional air is mixed therewith, which air is supplied through the outlet 18 of the conduits 9. The gases and air are further heated by contact 95 with the walls of partition 14 and are ig- 100

105

110

nited when leaving the lower open edge 17 of said partition. The flame rising from said burning gases and extending into the flues 2 is provided with additional oxygen 5 to insure complete combustion thereof by hot air which is delivered through the perforated pipes 19 in the compartment 20.

Although but one specific embodiment of this invention has been herein shown and 10 described, it will be understood that numerous details of the construction shown may be altered or omitted without departing from the spirit of this invention as defined by the following claims.

15 I claim:—

1. In a furnace, a furnace chamber comprising surrounding walls and a grate, a transversely extending wall separating said furnace compartment into two divisions, 20 said wall being located approximately one-fourth the distance from the rear of said furnace chamber and arranged to close the upper part of said furnace chamber while providing communication between the two 25 divisions of said chamber at the lower end of said wall, said wall being provided with a vertically extending passage open at its lower end and communicating above said lower end with the larger of said divisions 30 of the furnace chamber, a conduit extending upwardly from the ash-pit and extending into the smaller of said divisions and from there leading into the larger of said divisions and having an outlet for air in the 35 larger of said divisions.

2. In a furnace, a furnace chamber comprising surrounding walls and a grate, a transversely extending wall separating said furnace compartment into two divisions, 40 said wall being located approximately one-fourth the distance from the rear of said furnace chamber and arranged to close the upper part of said furnace chamber while providing communication between the two 45 divisions of said chamber at the lower end of said wall, said wall being provided with a vertically extending passage open at its lower end and communicating above said lower end with the larger of said divisions 50 of the furnace chamber, a conduit extending upwardly from the ash-pit and extending into the smaller of said divisions and from there leading into the larger of said divisions and having outlets for air in the vertically 55 extending passage of said dividing wall and in the larger of said divisions.

3. In a furnace, a furnace chamber comprising surrounding walls and a grate, a transversely extending wall separating said 60 furnace compartment into two divisions, said wall being located approximately one-fourth the distance from the rear of said furnace chamber and arranged to close the upper part of said furnace chamber while 65 providing communication between the two

divisions of said chamber at the lower end of said wall, said wall being provided with a vertically extending passage open at its lower end and communicating above said lower end with the larger of said divisions of the furnace chamber, a conduit extending upwardly from the ash-pit and extending into the smaller of said divisions and from there leading into the larger of said divisions and having outlets for air in 75 the smaller of said divisions, in the vertically extending passage in said wall, and in the larger of said divisions.

4. A furnace, comprising a furnace chamber having surrounding walls and a grate, a transversely extending partition dividing 80 said chamber into two unequal divisions, said partition being provided with a conduit to permit the passage of gases and air from the larger to the smaller of said divisions, a conduit extending from the ash-pit 85 upwardly into the larger of said divisions and from this into the smaller of said divisions and returning into the larger of said divisions, said conduit having an outlet in 90 the larger of said divisions.

5. A furnace, comprising a furnace chamber having surrounding walls and a grate, a transversely extending partition dividing 95 said chamber into two unequal divisions, said partition being provided with a conduit to permit the passage of gases and air from the larger to the smaller of said divisions, a conduit extending from the ash-pit upwardly into the larger of said divisions and 100 from this into the smaller of said divisions and returning into the larger of said divisions, said conduit having outlets in the passage in said partition and in the larger of said divisions.

6. A furnace, comprising a furnace chamber having surrounding walls and a grate, a transversely extending partition dividing 105 said chamber into two divisions, said partition being provided with a conduit to permit the passage of gases and air from one to the other of said divisions, a conduit extending upwardly from the ash-pit and extending into the rear one of said divisions and from there leading into the forward one of 110 said divisions and having an outlet for air therein at the forward end of said forward division.

7. A furnace comprising surrounding walls, a grate, an ash-pit, and a boiler, a transverse wall depending from the roof of 115 the furnace and dividing it into two compartments but arranged to provide restricted communication between said compartments, and a conduit having an inlet in the ash-pit, said conduit extending upwardly 120 into the forward compartment and then adjacent the boiler surface to the rear compartment of the furnace and returning also adjacent the boiler surface to the forward 125 130

compartment, the conduit being provided with an outlet in the forward compartment of the furnace.

8. A furnace comprising surrounding walls, a grate, an ashpit and a boiler, a transverse wall depending from the roof of the furnace and dividing it into two compartments, said transverse wall being arranged to provide restricted communication

between said compartments and a conduit 10 having an inlet in the ashpit, said conduit having a portion of its length located in the rear compartment and being provided with an outlet in the forward compartment.

Signed at Chicago this 3d day of March, 15 1916.

IRA W. FOLTZ.
